UNITED STATES PATENT OFFICE.

CHARLES ARTHUR BILESTINE, OF TOLEDO, OHIO.

OARING DEVICE FOR ROWBOATS.

Application filed March 12, 1928. Serial No. 261,082.

This invention relates to new and useful improvements in oaring devices for row boats, canoes, skiffs, dories and other hand propelled boats, and aims to provide an oaring device wherein the rearward movement of the oar blades is occasioned by the rearward movement of complemental handles so that the boat can be properly propelled in the direction facing the oarsman with the obvious result of enabling the oarsman to row a steady course.

In carrying out the invention there is provided a pair of similarly constructed units each of which includes generally a plate pivoted to the gunwale of the boat and upon which is mounted a pair of handle members the inner ends thereof having intermeshing gears of predetermined ratio.

The plate is reversible so that either of the handle members may detachably receive the oar blades so that the boat can be propelled at high speed, necessitating greater effort on the part of the oarsman, or at low speed requiring less effort on the part of the oarsman.

An important object of this invention resides in the provision of an oaring device that is of simple construction and that may be attached to the gunwale of a boat without in any way whatever altering the construction of the boat.

With the foregoing and other objects in view as the nature of the invention will be better understood, the same comprises the novel form, combination and arrangement of parts hereinafter more fully described, shown in the accompanying drawings and claimed.

In the accompanying drawings wherein like reference characters indicate corresponding parts throughout the several views:

Figure 1 is a fragmentary plan view of the rear end of a row boat or the like equipped with a pair of the oaring devices constructed in accordance with the invention.

Figure 2 is a fragmentary transverse section through the top board of one of the boat gunwales disclosing the oaring device in side elevation.

Figure 3 is a bottom plan view of the device per se, the oar blade being removed.

Figure 4 is a fragmentary section through said plate member, and one of the handle members within which is arranged the oar blade.

Figure 5 is a section through the handle

member and the oar blade disclosing more clearly the manner of detachable connection between the member and said oar blades, and

Figure 6 is a fragmentary plan view of one of the boat gunwales and one of the oaring devices in this instance the device being reversed from the position as disclosed in Figure 1.

Now having particular reference to the drawings, A designates a row boat or similar hand propelled craft, while B—B designate generally a pair of the oaring devices constructed in accordance with the present invention as associated with the gunwales of the boat directly in front of the oarsman's seat. The oaring device consists of a pair of spaced parallel attaching straps 5—5 having openings therein to permit of their attachment of the gunwale of the boat transversely thereof through the medium of screws or other similar fasteners. The inner ends of these straps 5—5 are interconnected by an arcuate bridge piece 7 that extends considerably above the straps 5—5 to serve as a resting block as will be presently brought out.

The forward ends of these straps 5—5 are provided with upstanding ears 8—8 that are formed with aligned openings to provide bearings for the pintle ends 9—9 of a rock shaft 10. This rock shaft 10 is formed or associated otherwise with the bottom surface and substantially intermediate the ends of a right angularly extending plate 11.

Pivoted upon the top side of this plate 11 at opposite sides of the center thereof is a pair of intermeshing gears 12—12, the ratio of which with respect to each other is preferably two to one.

The periphery of each of these gears is formed or constructed with a radial tubular member 13 to provide an actuating handle or a holder for an oar blade 14, the inner end of which is preferably of reduced diameter and of a size to provide a tight fit within either tubular member. Each tubular member is provided at its outer end with a flange 15 and with opposed openings 16 so that the said blade 14 may be secured within either tubular member through the medium of a locking pin 17, preferably of the readily removable type as disclosed in Figure 5.

Obviously the plate 11 may be pivotally arranged between the supporting straps 5—5 so that either one of the tubular members 13 may be employed as the actuating handle

so that when in the position as illustrated in Figure 1 the reverse motions of the innermost tubular members will result in the rapid movement of the oar blades, whereas when 5 the devices are reversed as disclosed in Figure 6 a slower motion of the blades will be had. Obviously, by reason of the pivotal attachment of the plate 11, the oar blades may be readily raised from or lowered into the water, 10 while when raised the plate may be supported upon the bridge pieces 7.

In view of the foregoing description when considered in conjunction with the accompanying drawings it will be apparent that I 15 have provided a highly novel, simple and extremely useful oaring device that is to be used on all hand propelled boats, and even though I have herein shown and described the invention as consisting of certain detail structural elements, it is nevertheless to be understood that some changes may be made therein 20

without affecting the spirit and scope of the appended claim.

Having thus described the invention, what I claim is:

In an oaring device of the character described, a base member adapted for longitudinal arrangement upon the gunwale of a boat, a transversely extending plate pivoted to said base member so that the same may rock laterally thereon, a pair of intermeshing gears mounted for rotation upon the surface of the plate construction extending radially from each gear to provide hand and oar receiving sockets, said gears being of different sizes so as to regulate the sweep of the oar blades, and an arcuate shaped member supported below the inner end of the plate and upon which the plate may ride. 25 30 35

In testimony whereof I affix my signature.

CHARLES ARTHUR BILESTINE.
